VALVE FOR HEATING SYSTEMS

Charles B. Simoneau, Lynn, Mass.

Application December 3, 1935, Serial No. 52,670
Renewed March 14, 1938

7 Claims. (Cl. 236—61)

My present invention comprises a dual-float, vacuum check, thermostatic valve, with dual vent control, for use on radiators of heating systems. It provides novel means for maintaining the valve in closed position, for increasing the period of valve closure during heat rest periods, for providing regulated control of air venting, for increasing and retarding the speed of venting all radiators in a heating system with resultant uniform delivery of heat to the radiators, and the maintenance of vacuums in the valve units and radiators whereby the speed of heating is accelerated. Other advantages, not mentioned herein, will be understood by those skilled in the art.

15 The drawing that accompanies this application for a patent as a part thereof shows a valve unit partly in longitudinal section.

Referring to the drawing, I provide a base 1 of usual construction having an externally threaded port 2 and a drain tube 3, a cylindrical casing 4 mounted on base 1 as at 5, the casing having a top 6 mounted as at 7, the joints 5 and 7 being of suitable construction to prevent leaking, base 1, casing 4 and top 6 forming a chamber 8 operatively connected with the heating system (not shown) through port 2. At the bottom of chamber 8 is a rectangular plate 9 having at its center an upwardly projecting part 10. Normally resting on plate 9 is a thermostatic, hermetically sealed float 11, the bottom of which 11a is flexible, normally concave with relation to projection 10 and recessed by means of an annular groove 11b so that the lower edge of the float rests normally upon plate 9. Within float 11 is a volatile fluid which is expansible upon application of heat thereto. A plate 9a is affixed to the top of float 11 and has a projection 9b thereon. Positioned on plate 9a is a second float 12, of similar construction as float 11 except that it is not sealed. Normally, the lower edge of float 12 rests upon plate 9a. Projecting from the top of float 12 is a conical valve 13. Adjustably mounted in the top of the casing is a valve seat 14 having external threads 14a which engage internal threads 6a in top 6, and positioned to receive valve 13. A bore 13a extends longitudinally through valve 13 to the interior of float 12 and is smaller in diameter than the port. A tube 15 projects from float 12 through valve 13 and port 14, the lower end of the tube being preferably near the bottom of the float and its upper end extending beyond the outer end of the valve seat to near the top of cap 16. This tube is held in fixed position with relation to float 12 by swaging the valve around it or by other suitable means. Mounted on the

top of the casing is a vent cap 16 having in its side a vent 16a and in its top an internally threaded opening 16b adapted to receive an externally threaded vent tube 17 of smaller external diameter than the valve seat structure 14 and of greater internal diameter than tube 15 and port 14. The top of tube 17 is provided with a boss 17a by which the tube may be turned for adjustment purposes as will be described herein-after, and in the boss is a vent 17b from tube 17. 5 10

When my device is in operative position on a radiator the introduction of steam forces out any air that may be in the heating system until steam enters chamber 8 in the unit to expand the volatile fluid in float 11, which expansion distends bottom 11a of float 11 against projection 10 and causes float 12 and valve 13 to rise and close port 14. When steam lessens in the unit a vacuum is created in chamber 8, float 11 contracts and atmospheric pressure through tube 15 is exerted upon the flexible bottom 12a of float 12; but its expansion is delayed by the upward pressure of float 11 until the bottom of float 11 has receded to its normal concave position, the bottom 12a of float 12 continuing to expand until the 25 vacuum is overcome by the opening of the valve. Port 14 having been adjusted with relation to valve 13 in assembling the unit to prevent continual closure of the port when bottom 12a of float 21 is fully distended and bottom 11a of float 30 11 is in normal concave position, when the flexible bottoms have reached these positions valve 13 recedes from port 14 to open position.

While the valve is in closed position, the lessening of steam in the unit creates a vacuum therein and this vacuum is maintained until the valve opens as described, thus preventing the entrance of cold air to chill the heating system during usual intermittent rest periods of the heater. This vacuum also draws steam into the system 40 during such rest periods. Upon resumption of steam projection into the system the vacuum eliminates the necessity of forcing air from the system, thus increasing the speed of heating, as under ordinary operating conditions little or no air is admitted to the system for the reason that in practice the unit seldom becomes cool enough to recede and open the port during intermittent rest periods.

By means of my vent regulator the amount of air to be vented from the radiators is controlled and balanced in a manner that has not been heretofore practiced. This regulator supplies means for control of venting so that air may be 55

vented through vent 17b acting alone or through vent 17b and vent 16a acting together.

In the event that water enters the unit, it causes float 11 to rise and carry with it float 12 5 and valve 13 to close port 14. If the water continues to rise thereafter, float 11 becomes submerged and its increased buoyancy resulting therefrom maintains valve 13 in firmly closed position, thus preventing water from passing 10 therethrough, and the valve remains closed until the water has receded from the unit.

For single venting, tube 17 is screwed down to meet the top of valve seat 14, thus closing vent 16a and venting takes place only through 17b. 15 To obtain venting through both vents, tube 17 is turned to raise its lower end from valve seat 14. The amount of venting is thus regulated to the needs of the radiator. In this way the amount 20 of venting at any radiator throughout the heat distributing system is adjustable according to the position of the radiator with relation to the heater, the more distant radiators being provided with free venting than those nearer to the heater with resultant speeding up of the heating of the 25 radiators in a manner that will be understood by those skilled in the art, the more remote radiators being thus heated more quickly and more uniformly with relation to the nearer radiators than heretofore.

30 As is known to those skilled in the art and to users of radiator valves, occasions arise when, by reason of deposits of solid material, the valves become clogged so as to prevent free passage of air therefrom, with resultant slowing down of the free entry of the heating medium to the radiators. I provide a simple means for correcting 35 this condition without removing the valve from the radiator. This comprises the removal of vent tube 17 and with a piece of metal or other convenient article shaped to reach the upper end 40 of tube 15, pressing down upon the tube so that valve 13 recedes from valve port 14, whereupon steam pressure will drive steam through the port and clean the valve in a manner that will be readily understood.

45 My invention is illustrated in the drawing and described herein for the purpose of explanation; but I do not mean to be limited thereby as modifications thereof performing the functions thereof of come within its scope.

50 Having described my invention and its mode of operation, what I claim is:

1. In a device of the class described having a valve mounted upon a float and a valve port for venting, means for providing regulated control of venting, said means comprising a vent cap, a vent in said cap, a movable vent tube mounted in said cap, a vent in said vent tube, a tube mounted in the valve float and projecting into the vent tube and means on the vent tube for moving said vent tube towards and away from the valve port, as described.

2. In a device of the class described having a valve and adjustable valve port for vent control, means for closing the valve, said means comprising a thermostatic float, a flexible float open to atmospheric pressure and having mounted thereon said valve positioned to close the valve port upon expansion of the thermostatic float and means for providing regulated control of venting, said means comprising a vent cap, a vent in said cap, a movable vent tube mounted in said cap, a

vent in said vent tube, a tube mounted in the valve float and projecting into the vent tube and means on the vent tube for moving the vent tube towards and away from the valve port, as described.

3. In a device of the class described having a valve and adjustable valve port for vent control, means for closing the valve and holding the valve in closed position, said means comprising a thermostatic float, a flexible valve float having mounted thereon said valve positioned to close the valve port upon expansion of the thermostatic float, the flexible valve float being open to atmospheric pressure and expanded thereby upon contraction of the thermostatic float, and means for providing regulated control of venting, said means comprising a vent cap, a vent in said cap, a movable vent tube mounted in said cap, a vent in said vent tube, a tube mounted in the valve float and projecting into the vent tube and means on the vent tube for moving the vent tube towards and away from the valve port, as described.

4. In a device of the class described, means for providing regulated control of venting, said means comprising a vent cap, a vent in said cap, a movable vent tube mounted in said cap, a vent in said vent tube, the vent in the cap and the vent in the tube venting to the atmosphere independently of each other and means on the vent tube for moving said vent tube towards and away from the valve port to vary the effectiveness of the cap vent.

5. In a device of the class described, means for providing regulated control of venting, said means comprising an adjustable valve port, a vent cap, a vent in said cap, a movable vent tube mounted in said cap, a vent in said vent tube, the vent in the cap and the vent in the tube venting to the atmosphere independently of each other and means on the vent tube for moving the vent tube towards and away from the valve port to vary the effectiveness of the cap vent.

6. In a device of the class described having a valve mounted upon a float, means for providing regulated control of venting, said means comprising an adjustable valve port, a vent cap, a vent in said cap, a movable vent tube mounted in said cap, a vent in said vent tube, a tube mounted in the valve float and projecting into the vent tube, and means on the vent tube for moving the vent tube towards and away from the valve port, as described.

7. In a device of the class described having a valve and valve port for venting, means for closing the valve and holding the valve in closed position, said means comprising a thermostatic float, a flexible valve float having mounted thereon said valve to close the valve port upon expansion of the thermostatic float, the flexible float being open to atmospheric pressure and expanded thereby upon contraction of the thermostatic float, and means for providing regulated control of venting, said means comprising a valve port adjustable with relation to the valve, a vent cap, a vent in said cap, a movable vent tube mounted in said cap, a vent in said vent tube, a tube mounted in the valve float and projecting into the vent tube, and means on the vent tube for moving the vent tube towards and away from the valve port, as described.
